Term of patent 14 years

(Cl. D90—20)

Fig. 1

FIG. 2

FIG. 3

FIG. 1 is a perspective view of a tire showing my new design, it being understood that the sidewall pattern shown is repeated throughout the circumference of the tire and the reverse side of the tire is identical with the side illustrated;

FIG. 2 is a fragmentary transverse sectional view through the tire substantially on the offset section indicating line 2-2 of FIG. 1 illustrating at the right-hand side of the figure one of the radial grooves of the design and at the left-hand side of the figure another of the radial grooves of the design; and

FIG. 3 is an enlarged fragmentary view in said elevation of the tire shown in FIG. 1.

The dominant features of my design reside in those portions shown in full lines.

I claim:

The ornamental design for a tire, substantially as shown and described.
